UNITED STATES PATENT OFFICE.

CHARLES OLSON, OF GRAND RAPIDS, MICHIGAN.

STEAM-BOILER.

SPECIFICATION forming part of Letters Patent No. 709,032, dated September 16, 1902.

Application filed March 26, 1902. Serial No. 100,041. (No model.)

To all whom it may concern:

Be it known that I, CHARLES OLSON, a citizen of the United States, residing at Grand Rapids, in the county of Kent and State of Michigan, have invented certain new and useful Improvements in Steam-Boilers; and I do hereby declare the following to be a full, clear, and exact description of the invention, such as will enable others skilled in the art to which it appertains to make and use the same.

My invention relates to improvements in steam-boilers, and more especially to small boilers adapted to be taken apart for cleaning and repairing; and its object is to provide improved means for detachably securing the parts in place and also improved means for packing the joint between the shell and heads and to provide the device with certain new and useful features hereinafter more fully described, and particularly pointed out in the claims, reference being had to the accompanying drawings, in which—

Figure 1 is a side elevation of a boiler embodying my invention; Fig. 2, a plan view of the same; and Fig. 3, an enlarged detail shown in vertical section, showing the construction of the same.

A represents the shell, which consists of a plain tube externally threaded at the ends.

B B are annular caps screw-threaded to fit the threads of the shell and detachably secured to the shell thereby and also having a large central opening to expose the ends of the flues.

C represents set-screws in the caps arranged at regular intervals and extending inward therefrom to engage a ring G, preferably of cast-iron or steel, and adapted to engage a gasket F, of suitable material, preferably soft copper.

D D are boiler-heads of such diameter that they will pass freely within the shell A and are connected by the flues E E', secured thereto at each end in the usual way. The outer tubes E', however, are arranged in a circle equidistant from the peripheries of the heads to evenly support the same all around against the pressure of the set-screw C'. The ring

G is adapted to slightly yield vertically under the pressure of the respective screws C, whereby any leak at any particular point may be cured by tightening the screws near the

same, and at the same time said ring is stiff enough to properly press the gasket against the head and shell between the screws. By slackening off the screws C one or both of the caps may be detached from the shell and the heads and tubes removed for the purpose of cleaning or repairs.

Having thus fully described my invention, what I claim, and desire to secure by Letters Patent, is—

1. In a boiler, the combination of a tubular shell, an annular cap detachably secured thereto, removable heads and flues, a gasket, a ring engaging the gasket, and set-screws in the cap engaging the ring, substantially as described.

2. In a boiler, the combination of a plain tubular shell externally threaded at each end, annular internally-threaded caps having large central openings, set-screws at regular intervals in the caps, removable heads in the boiler, flues connecting the heads and attached thereto, a gasket covering the seam between the heads and shell, rings engaging the gasket and engaged by the set-screws, substantially as described.

3. The combination of a tubular shell, annular caps detachably secured thereto, set-screws at intervals in the caps, removable heads within the shell, flues connecting the heads and attached thereto, the outer flues being arranged in a circle and equidistant from the peripheries of the heads, gaskets covering the seam between the heads and shell, and rings engaging the gaskets and engaged by the set-screws, substantially as described.

4. In a boiler, the combination of a plain tubular shell externally threaded at the ends, internally-threaded caps having large central openings, set-screws at regular intervals in the caps, removable heads in the shell, flues connecting the heads, and arranged in a circle equidistant from the peripheries of the heads, gaskets covering the seams between the heads and shell, and yielding rings engaging the gaskets and engaged by the screws, substantially as described.

In testimony whereof I affix my signature in presence of two witnesses.

CHARLES OLSON.

Witnesses:

LUTHER V. MOULTON,
IDA THIEBOUT.
